UNITED STATES PATENT OFFICE

2,137,796

WAIST AND LIKE BELT AND BAND AND
THEIR FASTENING

Francis John Bayliss, Walsall, England

Application December 30, 1937, Serial No. 182,393
In Great Britain April 20, 1937

4 Claims. (Cl. 241—8)

This invention has reference to waist or like belts or bands and their fastenings and particularly to the kind wherein the fastening is resiliently connected to one end of the belt or band to provide a determined amount of resiliency to an otherwise inextensible article.

In the known kind of belt having the fastening resiliently connected thereto, springs have been applied between one end of the belt and the fastening, or alternatively, the springs have been applied between sections of the belt; however, in both cases the springs cause a rubbing action on wearing apparel which in the course of time damages the material.

The principal object of the present invention is to provide an improved belt or band wherein the resilient connection is associated with the belt or band in such a manner that the appearance of the article is unaltered, and the operation of the resilient means has no deleterious effect upon clothes with which the belt is worn.

The invention consists of an improved belt and fastening having the combination and arrangement providing a loop at one end of the belt or band, a buckle or clasp engaging the loop at its inner end to slide longitudinally within and over the loop, and an elastic tensioning member connected at one of its ends to the inner end of the buckle or clasp and connected at its other end to an inner portion of the loop, said member lying wholly within said loop and longitudinally thereof.

In the drawing

Fig. 1 is a plan of a belt or band fitted with a tongued buckle.

Fig. 2 is a plan on an enlarged scale of one end of the belt, Fig. 1.

Fig. 3 is a longitudinal section of Fig. 2 taken on the broken lines *a*, *a*.

Fig. 4 is a plan of the buckle and its resilient connection before application to the belt or band.

One end of a leather or like belt 1 is doubled upon itself at 2 to provide a loop 3, the end of the doubled over portion being sewn to the adjacent portion at 4, 4, to thereby provide a channel or housing 5 for the purpose hereinafter described. A buckle 6 having a tongue 7 pivoted on the buckle-bar 8 is inserted in the loop 3 so that the buckle-bar 8 is slidable therein with

the tongue 7 slidably engaging a slot 9 in the outer end of the loop 3. The tongue 7 is, therefore, of the full length of the buckle. The buckle 6 is resiliently connected to the belt by two springs 10 having outer eyed ends 12 which are permanently connected to integral hooks 13 of a

connector 14 having sleeves 15 revolvably engaging said buckle-bar 8 while inner eyed ends 16 of said springs are connected to corresponding hooks of an attachment plate 17 riveted at 18 to the inside of the loop 3 as particularly seen from Fig. 3, the housing or channel 5 providing a guide for said springs 10.

When the otherwise inextensible belt is fastened round the wearer in the usual way, with one of the holes 19 co-operating with the tongue 10, the buckle 6 is capable of considerable longitudinal sliding movement relatively to the loop 3 occasioned by the extensible springs 10, the displacement of the buckle depending upon the abdominal or other movements of the wearer.

It will be seen that the inner buckle-bar 8, connector 14, springs 10 and the attachment plate 17 are normally wholly concealed in the loop 3, and, moreover, since none of the aforesaid parts are capable of contacting wearing apparel the latter cannot be rubbed or damaged during the use of the belt.

It is to be understood that the springs 10 are described and illustrated only by way of embodiment since any elastic member or members could be used in lieu thereof.

Having now described my invention, what I claim and desire to secure by Letters Patent is:

1. A belt, strap, or the like, having a permanent and flexible longitudinal loop at its one end, a buckle attached to said loop by one of its transverse bars passing therethrough to slide in said loop longitudinally thereof, and a flexible tension spring disposed longitudinally within said loop, said spring having one end in pivotal engagement with said transverse bar, the other end being secured to the inner extremity of said loop.

2. A belt, strap, or the like, having a permanent and flexible longitudinal loop at its one end, a buckle attached to said loop by one of its transverse bars passing therethrough to slide in said loop longitudinally thereof, a longitudinal channel formed in the inner portion of the loop by stitching the edges of the loop together, and a flexible tension spring disposed longitudinally in said channel to freely expand and contract therein, said spring having one end in pivotal engagement with said transverse bar, the other end being secured to the inner extremity of said loop.

3. A belt, strap, or the like, having a permanent and flexible loop at its one end, a buckle attached to said loop by one of its transverse bars passing therethrough to slide in said loop longitudinally thereof, a longitudinal channel formed in the inner portion of the loop by stitching the

edges of the loop together, a plurality of flexible coiled tension springs disposed longitudinally and parallel to each other in said channel to freely expand and contract therein, said springs having their inner ends connected to a common attachment plate secured to the inner extremity of said loop, the outer ends of the springs being connected to a common connector pivotally engaging said transverse bar.

10 4. A belt, strap, or the like, having at its one end a permanent and flexible longitudinal loop,

formed with a slot in its outer end, a buckle attached to said loop by one of its transverse bars passing therethrough to slide in said loop longitudinally thereof and having pivoted thereto a tongue projecting slidably and swingably through said slot, and a flexible tension spring longitudinally disposed within said loop, said spring having one end in pivotal engagement with said transverse bar, the other end being secured to the inner extremity of said loop. 5

FRANCIS JOHN BAYLISS.
